Specification for Design.

Patented Sept. 14, 1915.

Application filed November 24, 1914. Serial No. 873,834. Term of patent 14 years.

To all whom it may concern:

Be it known that I, HENRY S. SLAYTER, a subject of George V, King of Great Britain, residing at Belmont, county of Middlesex, Commonwealth of Massachusetts, have invented a new, original, and ornamental Design for Ornamented Paper, of which the following is a specification, reference being had to the accompanying drawing, forming a part thereof.

I claim,
The ornamental design for ornamented paper as shown.

HENRY S. SLAYTER.
